(57) **CLAIM**

The ornamental design for a mop head, as shown and described.

DESCRIPTION

FIG. 1 is a side elevation view of the mop head, embodying the new design, the opposite side is a mirror image thereto;

FIG. 2 is a front view thereof;

FIG. 3 is a back view thereof;

FIG. 4 is a top view thereof;

FIG. 5 is a perspective view thereof;

FIG. 6 is a side elevation view of a second embodiment of the mop head of FIG. 1 where the grippers are shown in broken lines, the opposite side is a mirror image thereto;

FIG. 7 is a front view of the mop head shown in FIG. 6;

FIG. 8 is a back view the mop head shown in FIG. 6;

FIG. 9 is a top view the mop head shown in FIG. 6; and,

FIG. 10 is a perspective view the mop head shown in FIG. 6.

The broken lines shown in the drawings are for illustrative purposes only and form no part of the claimed design.
